UNITED STATES PATENT OFFICE.

CHARLES E. HOPKINS, OF PLAINFIELD, NEW JERSEY; THE PLAINFIELD TRUST COMPANY ADMINISTRATOR OF SAID CHARLES E. HOPKINS, DECEASED.

CURVED-STEREOTYPE-PLATE-FINISHING MACHINE.

Original application filed February 15, 1913, Serial No. 748,692. Divided and this application filed September 9, 1918, Serial No. 253,301. Renewed September 27, 1924.

To all whom it may concern:

Be it known that I, CHARLES E. HOPKINS, a citizen of the United States, residing at Plainfield, in the county of Union and State 5 of New Jersey, have invented a new and useful Curved-Stereotype-Plate-Finishing Machine, of which the following is a specification.

This is a division of my Patent No. 1, 10 284,193 on a curved stereotype plate making machine, dated Nov. 5, 1918, originally filed February 15, 1913, Serial No. 748,692.

This invention can be embodied in a finishing mechanism comprising the usual plate 15 supporting arch, and shaving knife rotatable within and beneath the said arch. The principal objects of the invention are to provide a simple form of mechanism for operating the finishing device for simultaneously 20 and automatically clamping the plate in the arch and starting the machine, and for automatically stopping it in convenient position when the finishing operations are completed. I also have a circular saw or cutter 25 carried by the knife shaft for separating the riser portion from the type face portion of the stereotype plate. I also provide a trimmer or beveling tool for beveling the curved edge of the type face portion after the riser 30 has been separated therefrom by the saw. The different tools and devices are connected so as to be operated from one source of power.

Reference is to be had to the accompanying 35 drawings, in which—

Fig. 1 is a side elevation of a preferred form of the machine with the near side frame removed for the purpose of better illustrating same, and showing at one end a 40 supporting frame for a casting device, not shown;

Fig. 2 is a plan of the same;

Fig. 3 is a front end view with the plate 45 clamped in the arch, a part of the worm driving gear having been broken away to better illustrate the finishing device;

Fig. 4 is a front end view showing the plate in position ready to be clamped up in the arch and parts of the mechanism omitted;

Fig. 5 is a rear view with the plate lowered in the arch; and

Fig. 6 is a front view of the finishing arch and coacting plate lock, shaving knife, tail cutting saw, and beveling tool.

This finishing device is designed to co- 55 operate with a casting mechanism, not shown, but located at the front end of the finishing mechanism. The casting chamber may be formed by the usual concave segmental back and co-acting convex core and 60 other elements necessary. The complete casting mechanism comprises, besides the parts necessary to make up the casting chamber, a supporting frame 49 located at one side. The top edges of the frames 49 act as 65 a plate support or guide over which the plate can be moved to the finishing arch 50 when freed from the casting or mold members. These plate supports are located in alignment with like supports 77, 79 in the finish- 70 ing mechanism.

The plate supporting arch 50 is held in 75 position by side frames 51. The shaving knife shaft 52 operates in bearings formed in cross frames 53 and 54. The knife shaft 52 is provided with the usual adjustable shaving knife 55 which is arranged so that when a stereotype plate is positioned against the dome of the arch the knife will revolve 80 axially within the concavity of the plate and smooth off the ribs formed on the face of said concavity, thereby making each cast of a uniform thickness.

For the purpose of simplifying the construction, I have arranged a tail cutting saw 85 to travel with the knife shaft. The saw is mounted on one end of a shaft 57, operating in bearings 58 formed on the knife shaft; mounted on the opposite end of this shaft 57 is a gear 59 which meshes with a gear 90 60 loose on the knife shaft. Fast to this gear 60 is a chain sprocket 61 which is driven by a larger sprocket 62 fast on a shaft 63, one 95 end of which shaft is provided with a bevel gear 64 which meshes with a larger beveled gear 65 fast on the driving shaft 66. By this mechanism the saw is kept in constant rotation when the driving shaft is in motion. For the purpose of supplying a driving connection from any source of power there is 100 provided a driving pulley 102 attached to one end of the driving shaft 66.

The shaving knife 55, as is usually the case in combination shaving and trimming machines, extends only the length of the finished plate P. The saw 56 as shown simply cuts a groove through and around the circumference of the plate, thereby separating what is called the riser portion from the type face.

For the purpose of attaching these semi-cylindrical shells or plates to the cylinders of the printing presses, it is necessary to form the curved ends with a bevel. In this case the bottom bevel is formed in casting but I have provided a beveling tool 100 which I attach to one end of the knife shaft extension which carries the knife 55. This beveling tool is clearly shown in Figs. 2 and 6. In the latter view the tool is shown as in operation.

20 The driving mechanism as shown in Fig. 5 comprises the driving shaft 66 which operates in bearings 67 and 68 formed in the rear cross frame, and upon which is mounted the bevel gear 65 for driving the tail cutting saw mechanism. Mounted loose on the driving shaft 66 is a worm 69 which at all times meshes with a worm gear 70 fast on that end of the knife shaft 52. One end of the worm 69 is formed with clutch jaws 30 which engage or disengage a sliding jaw 71, slidingly keyed on the driving shaft 66.

The sliding clutch jaw 71 is formed with a groove in which operates an anti-friction roller 72 mounted on an upright arm 73 fast on one end of a rock shaft 74. Also fast on the rock shaft 74 are two upright arms 75-75 which engage beneath arms 76 formed on the roadway 77, the end of each of the said arms 76 being pivoted to the 40 end faces of the arch by studs 78-78 (see Fig. 1). As shown in Figs. 5 and 6 the opposite side of the arch 50 is provided with a fixed roadway or support 79.

It will be seen by the above that the act 45 of throwing in the clutch also forces the stereotype plate up into position against the dome of the arch.

The particular mechanism employed for throwing in the clutch, as well as positioning the stereotype up into the dome of the arch, is exceedingly simple and comprises a horizontal arm 81 pivoted to the top of the upright arm 73; the opposite end of the arm is located in the path of a pin 82 fast in the adjacent face of the worm gear wheel 70. This horizontal pivoted arm 81 is provided with an arm 83 extending at an angle upward; the upper end of this arm 83 engages a trip pawl 84 fast on a shaft 85 extending lengthwise of the finishing mechanism, and provided at the opposite end with an operating handle 85. By this mechanism the pin 82 on the worm gear 70 pushes the clutch members out of engagement after each revolution of the

knife shaft, holding same in that position until another stereotype plate has been properly positioned on the supports beneath the arch.

A heavy compressed coil spring 86 is located on a spring rod 87 engaging the pivot end of the horizontal trip arm 81. This spring is kept under tension especially when the machine is at rest, owing to its opposite end engaging with an extension 89 on the frame through which extension the spring rod 87 can operate. The purpose of this spring 86 is to advance the clutch jaw into engagement as well as elevate the plate lifter. For the purpose of positioning the stereotype plate lengthwise of the arch a stop 101 is fixed to the rear face of the arch.

The square end of the spring 86 engages against a square side face of the hub, thereby causing the spring to be held under a greater tension beneath the axis of the hub than above and always tending to restore the lever to horizontal position.

The operation is as follows: The plate 90 is supported on the frames 49 aligned with the finishing mechanism and free from the casting apparatus. The operator now pushes the plate axially beneath the arch until it comes solidly against the fixed stop 101. The plate is now in position or aligned with the finishing tools.

The operator now gives the starting or trip handle 85 a slight turn to the left in Fig. 5 which causes the cam trip pawl 84 100 to engage against the side of the arm 83, pushing it in. This action causes the co-acting trip arm 81 to pivot down and disengage its free end from the worm wheel pin 82. The forcing of the rock arm 81 105 from the engaging pin 82 allows the coil spring 86 to expand, thereby forcing the free end of the vertical rock lever 73 to rock inward. As this rock lever 73 is fastened on the shaft 74, the action of the spring causes the lever 75 to rock the plate lifter 77, thereby elevating and locking the cast plate up in the arch and in position to be operated upon by the finishing tool.

Of course as the operator has turned the 110 starting handle one complete turn in order to restore it to normal position, the pawl 84 allows the rock arm 83 to swing outward. This operation is aided by the spring 86.

The finishing begins by the revolving saw 120 56, separating the riser portion from the type face portion of the plate. As this operation nears the finish of its operation the beveling tool 100 begins its operation, then the shaving knife 55 commences shaving the ribs cast within the plate concavity.

When the shaving knife completes its operation the worm wheel pin 82 comes into engagement within the recess formed on the end of the rock lever arm 81. This 130

engagement causes the lever arm 81 to be forced back against the action of the coil spring 86, and the clutch jaw 71 to be forced out of engagement with its co-acting 5 jaw, formed on the worm 69. In this position the finishing tools have completed their cycle of motion. The plate lifter locking arms 76 are forced out of engagement with the plate lifter 77. This allows the 10 plate lifter to swing down and release the now finished plate, and once more align it with the fixed plate rail.

The operator now removes the riser portion of the cast and thereafter grasps the 15 finished plate, with a glove, and withdraws it from beneath the arch, and on the fixed plate rails. Afterward it is removed from the machine. During this finishing operation the operator is presumed to have made 20 another cast and got it ready to align with the finishing apparatus.

Although I have illustrated and described only one form of the invention, I am aware that many modifications can be made there- 25 in by any person skilled in the art without departing from the scope of the invention as expressed in the claims. Therefore I do not wish to be limited to all the details of construction herein shown and de- 30 scribed, but what I do claim is—

1. In a curved stereotype plate finishing machine, the combination of a tool supporting shaft, a finishing arch axially aligned with said shaft, a shaving knife on said shaft, means for revolving the tool supporting shaft, a saw rotatable as a whole with said shaft for cutting off the tail of the plate, and a beveling tool located to follow in the path of the saw as the tool supporting shaft revolves. 35

2. In a curved stereotype plate finishing machine, the combination of a plate supporting arch, a tool supporting shaft located beneath said arch, a gear at one end of said shaft, a clutch mechanism, a plate 45 lifting mechanism, and means on the gear for disengaging the clutch and simultaneously lowering the said plate lifter.

3. In a curved stereotype plate finishing machine, the combination of a tool supporting shaft, a plate supporting arch above said shaft, a gear on said shaft, a worm in mesh with said gear, a clutch arranged to engage or disengage the said worm, a plate lifter, and means for elevating the 50 plate lifter and moving the clutch into engagement with said worm. 55

In testimony whereof I have hereunto affixed my signature.

CHARLES E. HOPKINS.
